[57] ABSTRACT

The automatic sizing device of the present invention provides two amplifiers for low sensitivity range and for high sensitivity range and these amplifiers are used in the following manner. That is, the amplifier for the low sensitivity range is used in normal grinding for detecting a grinding limit for which the grinding speed and the amount of grinding are measured and the whole range of procedure of the grinding to an on size can be observed. During the above-mentioned normal grinding, the grinding speed is changed to the speed for precise grinding. And when the amplifier for high sensitivity range is used in a finishing grinding, a high accuracy for grinding can be obtained, and the signals for a spark out and for an on size can be precisely generated.

AUTOMATIC SIZING DEVICE FOR MEASURING APPARATUS

The present invention relates to an automatic sizing device of an automatic measuring apparatus, mainly utilized in an automatic grinding device.

An automatic measuring apparatus is one of a measuring control apparatus which directly measures a dimension of a work under grinding, applies the signal corresponding to a variation of the dimension of the work to the grinding device thereby controlling the grinding speed and the amount of the grinding, and stops the grinding motion when the dimension of the work reaches to an on size.

Generally used automatic measuring devices relate to the utilization of the analogue measuring technique. However, an accuracy limit in the analogue measurement does not generally exceed about $\pm 1 - 0.5$ percent of the full scale of the indicator used in the measuring device. Accordingly, when the full range of the indicator is utilized for observing the whole range of the procedure of the grinding to an on size, it is natural that the accuracy for a finishing grinding deteriorates.

The object of the present invention is to overcome the above-mentioned drawback.

Another object of the present invention is to provide an automatic sizing device which can observe the whole range of process of the grinding and simultaneously carries out a finishing grinding with a high accuracy.

Further object of the present invention is to provide an automatic sizing device which contains one amplifier for a normal grinding and another amplifier for a finishing grinding.

Further features and advantage of the present invention will be apparent from the ensuing description with reference to the accompanying drawings to which, however, the scope of the invention is in no way limited.

FIG. 1 shows a block diagram of one embodiment of a conventional sizing device of an automatic measuring apparatus,

FIG. 2 shows a block diagram of one embodiment of a sizing device of the present invention,

FIG. 3 shows a diagram explaining the relation between the variation of the dimension of the work and the reading of the indicator, and

FIG. 4 shows a circuit diagram of one embodiment of FIG. 2.

Referring to FIG. 1, an operation of a conventional automatic sizing device is carried out in the following manner. A grinder 1 of a grinding device contacts a work 2 grinding same. A variation of the dimension of the work 2 ground by the grinder 1 is converted to an electric output signal of a measuring unit part 3. The output signal of the measuring unit part 3 is supplied via an amplifier 4 to a synchronous rectifier 5. An exciting oscillator 10 is provided for exciting a detector in the measuring unit part 3 and the synchronous rectifier 5. The output of the synchronous rectifier 5 is supplied via trigger circuits 8 and 9 to relay driving circuits 13 and 14, and the control actions, that is, a high speed grinding, a finishing grinding, a grinding stop, a rear back of a grinder etc. are all carried out by the output of the relay driving circuit. In this case, the whole range of process of the grinding is observed by an indicator 11, and the trigger circuits 8 and 9 are operated by the

output of the synchronous rectifier 5 all over the whole range of procedure of the grinding. As a result, the accuracy for a finishing grinding deteriorates.

Referring to FIG. 2, the device according to the present invention has the same function as far as the synchronous rectifier 5. However, in the present invention, the output of the synchronous rectifier 5 is amplified by the first DC amplifier 6 and supplied via the first trigger circuits 8, 8', . . . to relay driving circuits 13, 13', . . . 10. Further, the other output of the first DC amplifier 6 is further amplified by the second DC amplifier 7 and supplied via the second trigger circuits 9, 9', . . . to relay driving circuits 14, 14', . . . The output of the DC amplifiers 6 and 7 are supplied to an indicator 11 via 15 input terminal L and H of the commutating switch 12, respectively. The output of the first trigger circuits 8, 8', . . . are provided for a wide range control signal, for example, the normal grinding, the high speed grinding, etc. On the other hand, the output of the second trigger 20 circuits 9, 9', . . . are provided for a narrow range control signal for precise grinding, for example, a finishing grinding, a grinding stop, a rear back of a grinder, etc. The control signals for the grinding device are generated at a predetermined value on the L range of the indicator 11 by setting a trigger level in the above-mentioned trigger circuits. The numbers of these control signals and these trigger circuits are different according to the number and the level of the control signal. According to the level, the relay driving circuit is 25 connected to the first DC amplifier 6 or the second DC amplifier 7, and if necessary, directly to the synchronous rectifier 5 or to a third DC amplifier specially provided.

A scale state of the above-mentioned indicator 11 is 35 shown in FIG. 3. Referring to FIG. 3, the abscissa indicates the variation of the dimension of the work, the ordinate shows the reading of the indicator 11, and a dotted line FS shows the full scale of the indicator 11. The straight line B shows the low sensitivity range obtained via input terminal L which corresponds to the input of the first trigger circuits 8, 8', . . . and the straight line A shows the high sensitivity range obtained via input terminal H which corresponds to the input of the second trigger circuits 9, 9', . . . It is seen that the straight line B shows the whole range of a variation of the dimension of the work 2 and the straight line A shows the narrow range near the on size of the work 2, that is, the straight line A is an enlargement of the straight line B near the on size. Of course, the cross point of the straight lines A and B is an on size position. Further, as mentioned above, the control signals are generated on the appropriate points on the straight lines by setting a trigger level of the trigger circuit. Also, it is seen that the switch 12 indicates only the actual value, and the accuracy of the on size of the work is determined by the output of the trigger circuits 9, 9', . . . , thereby ensuring a high degree of accuracy.

FIG. 4 shows the circuit block diagram of the automatic circuit device of the present invention. The following explanation is given for the case where two trigger circuits and two control signals are provided in the device. Referring to FIG. 4, the measuring part 3 is composed of a differential transformer T, the primary winding thereof is excited by the exciting oscillator 10. A feeler F displaces in accordance with a variation of the dimension of the work, and the output of the measuring unit part 3 varies with the position of the feeler

F. A mean output level of the measuring part 3 is fixed at a proper measuring level by the potentiometer RV_1 , and is applied via the amplifier 4 to a primary winding of the transformer T_2 of the synchronous rectifier 5. In addition, another output of the exciting oscillator 10 is applied via a transformer T_3 between a neutral top on the secondary winding of the transformer T_2 and ground. DC output of the synchronous rectifier circuit 5 is applied to the first DC amplifier and this output of the first DC amplifier is always indicated by the low sensitivity range of the indicator 11. An output of the first DC amplifier is also applied to the first trigger circuit 8, and to the second DC amplifier 7. The output of the second DC amplifier is indicated, if necessary, by the high sensitivity range of the indicator 11 and is also applied to the second trigger circuit 9.

The trigger circuit 8 and 9 have essentially the same function, therefore it is sufficient to explain only the trigger circuit 8. The trigger circuit 8 is basically a schumit trigger circuit, and consists of an operational amplifier A_1 composed of an integrated circuit, a positive feedback means comprising R_1 , R_2 and R_3 , a level setting means composed of a positive potential level $+B_2$, a negative potential level, and a potentiometer RV_2 . The variable point of the potentiometer RV_2 is set in the position where a predetermined control signal for the normal grinding is generated. When the output level of the first DC amplifier exceeds the above-mentioned set level, the above-mentioned trigger circuit changes its binary level state. This changed level is amplified by a transistor TR_1 and causes a current to flow in the coil of the relay R. The relay contacts R-a, R-b and R-c are operated by the current flow in the coil and form the control output signals.

In the operation of the above-mentioned circuit, firstly a master is placed in the position of the work 2, and determines the condition of the high speed cutting, the finishing grinding, a spark out, the rear back of the grinder, etc. Working condition of the work 2 is detected by the measuring unit part 3, and a speed change of the high speed cutting and the finishing grinding etc. are controlled by the output of the trigger circuit 8, and the spark out and the rear back of the grinder etc. are controlled by the output of the trigger circuit 9.

What is claimed is:

1. An automatic sizing device for measuring appara-

tus comprising, means for detecting a variation of a dimension of a work, converting means for converting said variation into an electric quantity, an output of said converting means being applied via a synchronous rectifier to first amplifier means, an output of said first amplifier means being indicated on an indicator as a variation of a whole range of process of a grinding, an output of said first amplifier means being applied to a single or multiple first trigger circuits, outputs of said 10 first trigger circuits generating a single or multiple control signals for controlling a working condition of said work, said output of said first amplifier means being applied via second amplifier means to a single or multiple second trigger circuits, outputs of said second triggers circuit generating a single or multiple control signals for controlling a working condition near and/or on size.

2. The automatic sizing device for measuring apparatus according to claim 1, wherein said first and second trigger circuits each include, respectively, an operational amplifier with a positive feed back and a potentiometer for setting a trigger level of said operational amplifier, an output of said operational amplifier triggered by said level of said potentiometer is applied to a coil of a relay and the current flow in said coil actuates a 20 relay contact of said relay.

3. The automatic sizing device for measuring apparatus according to claim 1 in which each of said first and each of said second trigger circuits includes means for setting an individual trigger level whereby a control signal is generated only when (1) said first amplifier means output exceeds in value the individual trigger level of a first trigger circuit or (2) said second amplifier means output exceeds in value the individual trigger level of a second trigger circuit.

4. The automatic sizing device for measuring apparatus according to claim 1 in which each said first trigger circuit includes means for setting a first trigger level, means for providing a working condition control signal when each first trigger level is exceeded by the output 40 level of said first amplifier means,

each said second trigger circuit includes means for setting a second trigger level, means for providing an on size working condition control signal when each second trigger level is exceeded by the output level of said second amplifier means.
